UNITED STATES PATENT OFFICE

EARL R. SWANSON, OF CHICAGO, ILLINOIS, ASSIGNOR TO CHICAGO-CLEVELAND CAR ROOFING COMPANY, OF CHICAGO, ILLINOIS, A CORPORATION OF DELAWARE

RAILWAY CAR

Application filed July 31, 1930. Serial No. 472,169.

My invention relates to railway cars and more particularly to the embodiment in the roof structures of railway cars of the box type of means adapted to cooperate with 5 load lifting devices.

A principal object of the invention is to provide the roof with simple and rugged means of the character described which may be associated with the roof in such manner 10 as not to interfere with the loading of lading within the car.

A primary feature of the invention consists in providing the car with a longitudinally extending portion projecting upwardly 15 above the car roof and in associating therewith members adapted to serve as supports for load lifting devices.

Another feature of the invention resides in providing a roof having downwardly extending carlines with a longitudinally arranged beam disposed in overlapping relation with the outer faces of the roof sheets, and in associating with the beam a plurality 20 of members extending transversely of the car beneath the roof sheets, said members being adapted to serve as supports for load lifting devices.

Another feature of the invention consists in providing the roof sheets with an upwardly projecting longitudinally extending corrugation, and in associating therewith means cooperable with load lifting devices.

Other and more specific features of the invention residing in advantageous forms, 35 combinations and relations of parts will hereinafter appear and be pointed out in the claims.

In the drawings illustrating preferred 40 embodiments of the invention:

Figure 1 is a fragmentary longitudinal sectional view of a railway box car.

Figure 2 is a fragmentary sectional view taken on line 2—2, Figure 1.

Figure 3 is an enlarged fragmentary 45 sectional view taken on line 3—3, Figure 1.

Figure 4 is a fragmentary sectional view taken on line 4—4, Figure 3.

Figure 5 is a sectional view similar to Figure 1 illustrating a modified form of the invention.

Figure 6 is a fragmentary sectional view taken on line 6—6, Figure 5.

Figure 7 is an enlarged fragmentary sectional view taken on line 7—7, Figure 5.

Figure 8 is a fragmentary sectional view 55 taken on line 8—8, Figure 7.

Figure 9 is a sectional view corresponding to Figure 7 illustrating still another modified form of the invention.

Referring more particularly to the drawings 1 and 2 respectively designate the rigidly connected side and end plates of a railway box car. Extending transversely of the car and continuously from one side thereof to the other are carlines 3. Each of the carlines is of substantially channel shape having a web 4, upwardly projecting slightly diverging legs 5 and oppositely disposed laterally projecting flanges 6. The carlines may advantageously progressively decrease in height from adjacent the ridge of the roof and at their ends they may be provided with downturned flanges 6^a for attachment to adjoining portions of the side plates by rivets 7. Spanning the spaces between the carlines and the side plates are roof sheets 8 each of which is rigidly secured by rivets 9 to the lateral flanges 6 of the carlines. The sheets are so arranged that they close or bridge the channel portions of the carlines and the outer edges of the end roof sheets may be conveniently flanged downwardly as at 10 for attachment by rivets 11 to adjacent portions of the end plates 2. 70

Disposed above and in spaced relation to the roof sheets is a running board which may advantageously be formed by a plurality of planks 12. The planks are preferably connected by angle members 13 rigidly secured to the roof sheets and carlines by brackets 14 respectively disposed on opposite sides of the ridge of the roof. At their ends the planks may be connected to each other and to the end plates by brackets 15. 85

Extending longitudinally of the car and preferably continuously from adjacent one end thereof to the other is a beam 16. The beam is of inverted channel shape having a web 17, downwardly extending legs 18 and 100

oppositely disposed laterally projecting flanges 19, the latter being disposed in overlapping relation to the roof sheets. Intermediate their ends the flanges may be connected to the lateral flanges 6 of the carlines by adjacent rivets 9 while at their ends they are preferably connected to the end plates by angle shaped brackets 20, the brackets being secured to the end plates by rivets 11 10 and to the flanges by rivets 22.

Extending transversely of the car intermediate the carlines and beneath the roof sheets are a plurality of members 23. Each of these members is formed with a plate portion 24 and downwardly extending marginal flanges 25, the plate portion being connected to the lateral flanges 19 of the beam by rivets 26. The central portion of each of the members 23 is bowed or arched down- 15 wardly to afford a space between it and the adjacent portion of the roof sheet for receiving a rope, chain, nose of a hook or other suitable means capable of cooperating with a load lifting device. The forces imparted to the members 23 from load lifting devices are transmitted to the longitudinally extending beam 16 and from thence are equally distributed to adjacent carlines. By arranging the beam above the roof sheets it will 20 be perceived that it rests upon and is supported by the carlines and furthermore by securing it to the end plates and carlines it performs the function of the usual ridge pole. Also by arranging it between the running board and roof sheets it occupies a 25 space heretofore unused and the revenue earning capacity of the car is not impaired.

In Figures 5 to 8, inclusive, a slightly modified form of the invention is disclosed 40 employing a beam 27 having an arcuate portion 28 and laterally extending flanges 29. This beam is secured to the carlines and to the members 23 in the same manner in which the beam 16 is secured to these parts in the 45 principal figures of the drawings. However, to afford an increased space between the arched or bowed portions of the members 23 and adjacent portions of the roof sheets, the latter are integrally provided with corrugations 30 extending longitudinally of the car, preferably from one end thereof to the other. Since, as may be seen from the drawings, the corrugations 30 conform to the 50 arcuate portion of the beam 27 the strength 55 of the latter, as a beam, is materially increased. Thus a beam of less thickness may be used in this form of the invention than in the form illustrated in Figures 1 to 4, inclusive.

60 Instead of employing roof sheets which extend continuously from one side of the car to the other roof sheets of the type illustrated in Figure 9 may be used. As shown in this Figure the roof sheets only extend from 65 the sides of the car to adjacent the ridge of

the roof at which point they are arranged in overlapping relation. The overlapping portions of the sheets are integrally formed with upwardly projecting corrugations 32 which in effect constitute a beam on the opposite sides of which the carlines and supporting members 23 are rigidly secured by rivets 33. This particular construction is extremely rigid and due to the fact that the sheets are overlappingly secured together on opposite sides of their corrugations 32 the necessity for employing a separate beam similar to that illustrated in other forms of the invention is eliminated. 75

Although various forms of the invention 80 have been illustrated it will be appreciated that changes or modifications may be made in details of construction without departing from the spirit of the invention as defined by the following claims. 85

I claim:

1. A roof for railway cars involving roof sheets, carline means projecting below the roof sheets, a beam extending longitudinally of the car above the carlines and roof sheets, 90 and a plurality of members extending transversely of the car beneath the roof sheets, each of said members being rigidly secured to said beam and constituting means for supporting a load lifting device. 95

2. A roof for railway cars involving roof sheets, carlines depending below said roof sheets and rigidly secured to their undersides, a beam extending longitudinally of the car above the carlines and roof sheets, 100 and a plurality of members extending transversely of the car beneath the roof sheets and between the carlines, each of said members being rigidly secured to said beam and constituting means for supporting a load 105 lifting device. 110

3. A roof for railway cars involving roof sheets, carlines disposed beneath the roof sheets for supporting the latter, and a beam extending longitudinally of the car above the carlines and roof sheets, said beam having laterally projecting flanges disposed in overlapping relation to the outer faces of the roof sheets, and a plurality of members extending transversely of the car beneath the 115 roof sheets, each of said members being rigidly secured to the lateral flanges of the beam and being adapted to serve as a support for a load lifting device. 120

4. A roof for railway cars involving roof sheets, carlines depending below and rigidly secured to said roof sheets, a beam extending longitudinally of the car from adjacent one end thereof to adjacent the other, said beam being overlappingly secured to the outer faces of the roof sheets, and a plurality of members extending transversely of the car beneath the roof sheets and intermediate the carlines, each of said members being rigidly secured to said beam and constitut- 130

ing means for supporting a load lifting device.

5. A roof for railway cars involving roof sheets, carlines disposed beneath the roof sheets for supporting the latter, a beam of inverted channel-shape extending longitudinally of the car above the carlines and roof sheets, said beam being provided with oppositely disposed laterally projecting flanges rigidly secured to the roof sheets, and a plurality of members extending transversely of the car beneath the roof sheets, each of said members being rigidly secured to said beam and constituting means for supporting a load lifting device.

6. A roof for railway cars involving roof sheets, carlines depending below the roof sheets and having flanges secured to the undersides of the latter, a beam extending longitudinally of the car above the carlines and roof sheets, and a plurality of members extending transversely of the car beneath the roof sheets and intermediate the carlines, each of said members being rigidly secured to said beam and constituting means for supporting a load lifting device.

7. A roof for railway cars involving roof sheets, a plurality of carlines disposed beneath said roof sheets, each of said carlines being of substantially channel-shape and having a web and upwardly extending legs terminating in laterally projecting flanges, said flanges being rigidly secured to the undersides of the roof sheets, and a beam extending longitudinally of the car above the roof sheets and rigidly secured to the latter and to the flanges of the carlines, and a plurality of members extending transversely of the car beneath the roof sheets, each of said members being secured to said beam and being adapted to serve as a support for a load lifting device.

8. A roof for railway cars involving a plurality of roof sheets, said roof sheets having upwardly projecting longitudinally extending corrugations adjacent the ridge of the roof, members extending transversely of the car beneath the roof sheets and being rigidly secured to portions of the latter on opposite sides of said corrugations, each of said members being adapted to serve as a support for a load lifting device.

9. A roof for railway cars involving a plurality of roof sheets respectively extending continuously from one side of the roof to the other, each of said roof sheets being integrally formed with an upwardly projecting longitudinally extending corrugation, and members extending beneath said corrugations and respectively secured to portions of the roof sheets on opposite sides of the latter, each of said members constituting means adapted to serve as a support for a load lifting device.

10. A roof for railway cars involving a

plurality of roof sheets, each of said roof sheets being provided with an upwardly projecting longitudinally extending corrugation adjacent the ridge of the roof, and a beam extending longitudinally of the car 70 and rigidly secured to the roof sheets in overlapping relation to the corrugations of the latter, and members extending transversely of the car beneath said roof sheets, each of said members being rigidly secured to said beam on opposite sides of the corrugation and being adapted to serve as a support for a load lifting device. 75

11. A roof for railway cars involving a plurality of roof sheets respectively extending continuously from one side of the roof to the other, each of said roof sheets being provided adjacent the ridge of the roof with an upwardly projecting corrugation extending longitudinally of the car, and a beam 80 extending longitudinally of the car in overlapping relation to the corrugations of the roof sheets, said beam having laterally extending flanges rigidly secured to portions of the roof sheets on opposite sides of their corrugations, and members extending transversely of the car beneath the roof sheets, each of said members being rigidly secured to the flanges of the beam and being adapted to serve as a support for a load lifting 90 device. 95

12. A roof for railway cars involving a plurality of roof sheets, said sheets having portions arranged in overlapping relation adjacent the ridge of the roof, the overlapping portions of each roof sheet being provided with an upwardly projecting longitudinally extending corrugation, and a plurality of members extending transversely of the car beneath said corrugations, each 100 of said members being rigidly secured to portions of the roof sheets on opposite sides of the corrugation and being adapted to serve as means for supporting a load lifting 105 device. 110

13. A roof for railway cars involving a plurality of roof sheets, each of said roof sheets being integrally formed with portions adapted to overlap adjacent roof sheets at the ridge of the roof, said overlapping 115 portions being provided with upwardly projecting longitudinally extending corrugations, and members extending transversely of the car beneath the roof sheets, each of said members being rigidly secured to the overlapping portions of adjacent roof sheets 120 and having a portion disposed in spaced relation to the associated corrugations, the said portion of each member being adapted to serve as a support for a load lifting 125 device. 130

14. A roof for railway cars having a plurality of roof sheets, said sheets being provided with an upwardly projecting longitudinally extending rigidifying portion ad-

5 adjacent the ridge of the roof, carlines underlying and supporting the roof sheets, and means extending transversely of the car and rigidly secured to portions of the roof sheets adjacent said rigidifying portion, said means being adapted to serve as a support for a load lifting device.

10 15 15. A roof for railway cars involving roof sheets, carline means projecting below the roof sheets, a beam rigid with the roof and disposed in overlapping relation to the outer face of an adjacent roof sheet, and a member disposed beneath the roof sheets and between said carline means, said member being rigidly secured to the beam and constituting means for supporting a load lifting device.

In testimony whereof I affix my signature.
EARL R. SWANSON.
